(57) **CLAIM**

The ornamental design for a vehicle body, as shown and described.

DESCRIPTION

FIG. 1 is a front perspective view of a vehicle body showing the new design;

FIG. 2 is a side view thereof, the opposite side being a mirror image of that shown; and,

FIG. 3 is a rear perspective view thereof.

In the drawing views, the tires, emblems, grille, written matter and wheels shown in the broken lines are for illustrative purposes only and form no part of the claimed design.

1 Claim, 3 Drawing Sheets

FIG. 2

FIG. 3
